ICE TRAY

Frank J. Leyner, Lafayette, Colo.

REISSUED

Application August 27, 1932. Serial No. 630,640

2 Claims. (Cl. 62—108.5)

This invention relates to improvements in ice trays of the type employed in connection with mechanical refrigerators for the purpose of freezing ice cubes.

5 Since the adoption of mechanical refrigeration on a large scale for household use, the necessity of having some convenient way for freezing ice for use in preparing ice water and for other purposes, has been recognized and practically 10 every mechanical refrigerator is provided with some form of tray that can be filled with water and inserted into a compartment in the freezing unit, where the water will be subjected to such low temperature that it will congeal. Since water wets the surface of metal, it will naturally 15 adhere to the metal when frozen and it is therefore very difficult to remove the ice from the compartments of metal trays. The difficulty just mentioned has been recognized and many 20 attempts have been made to overcome it by changing the design of the trays or by making the trays of material whose surface is not appreciably wetted by the water and to which, therefore the ice does not readily adhere.

25 As an example of the class of trays just mentioned, attention is called to a type of trays made from rubber which can be employed in a manner analogous to the metal trays, but from which the ice cubes can be removed by bending the tray 30 or distorting it in such a way that the sides of the ice are loosened from the sides of the compartments.

It is the object of this invention to produce a tray that shall be especially well adapted for 35 use in freezing water to form ice cubes and whose construction makes it possible to release the ice cubes easily and quickly and without injury to the tray.

This invention, briefly described, consists of 40 a tray having a bottom formed from a thin, resilient, flexible sheet of metal, to one surface of which is secured by vulcanization, a mold having a plurality of compartments whose sides are formed from rubber and which are extensible to 45 some extent.

In normal position the bottom of the tray is straight so as to form a plain surface, but after the ice has been formed, the tray can be bent into such shape that the bottom is convex upwardly, thereby releasing the ice cubes from the upper surface of the bottom and from the sides 50 of the mold.

Having thus briefly described the invention, the same will now be described in detail, and for this 55 purpose reference will be had to the accompany-

ing drawing in which the preferred embodiment thereof has been illustrated, and in which:

Fig. 1 is a perspective view of a tray made in accordance with this invention;

Fig. 2 is a longitudinal section taken on line 60 2—2, Fig. 1, a portion of the tray having been removed so as to shorten the figure; and

Fig. 3 is a section taken on line 2—2, Fig. 1, and shows the bottom curved for the purpose of 65 releasing the ice cubes.

In the drawing reference numeral 4 designates the bottom of the tray which is formed from a thin sheet of metal, such as steel, which is readily bendable and which has sufficient resiliency to return it to original position when released. The 70

ends of the bottom are provided with handle portions 5 for convenience in inserting and removing the tray and for handling it. Secured to the upper surface of the bottom is a mold that is 75 formed from rubber composition. In the example shown, the mold has twenty-four openings or compartments that are formed, eight in length and three in width. The number of compartments, as well as their size, can be changed to 80

suit the conditions. The mold is provided with vertical sides and partitions which have been designated by reference numeral 6. These partitions may be of any suitable thickness and width and the entire mold portion is formed in one 85 unit. The lower edges of the partitions and sides 6 are attached to the upper surface of the bottom 4 by being vulcanized thereto as indicated at 7

in Figs. 2 and 3. The method of vulcanizing rubber to metal is well known and forms no part of 90 this invention. After the mold has been formed and attached to the upper surface of the bottom, the assembly has the appearance shown in Fig. 1 and a section like that shown in Figs. 2 and 3.

When ice is to be frozen, the several compartments are filled with water and the tray is then introduced into an opening provided therefor in the freezing unit of the refrigerator. After the 95 water has frozen, the tray can be removed and the bottom bent upwardly as shown in Fig. 3.

Since the ice cubes will not bend, it is apparent that there will be a force produced that tends to 100 separate the bottoms of the ice cubes from the upper surface of the metal bottom, thereby releasing the ice. The upward arching of the tray

also tends to lengthen the sides of the compartments and thereby producing forces that separate the ice from the sides of the compartments. After 105

the ice has been released, the tray will return to its original position by simply releasing the force 110 that is used for bending the same.

I am of course aware that the trays made entirely of rubber can be bent, but with such trays there is practically no force produced that tends to separate the bottoms of the ice cubes from the upper surface of the bottom of the compartments, because the entire tray is made of flexible rubber and therefore the flexure will take place at points between the ice cubes, whereas when a metal bottom is employed, a gradual curvature like that shown in Fig. 3 will tend to separate the ice from the bottom. Another advantage of a metal bottom over a rubber one is that it is a better conductor of heat and cold, and therefore the heat in the water will be more quickly abstracted than when a rubber tray is used and this results in a quicker freezing of the water.

Another advantage of the metal bottom is that it can have sufficient rigidity to support the tray without bending when the compartments are filled with water and this simplifies the handling of the tray.

With a tray like that shown and described and which has a sheet metal bottom that is a very good conductor of heat, it is apparent that as soon as the tray is removed from the refrigerator into a room of normal temperature, the heat surrounding the tray will pass through the bottom very quickly and serve to loosen the ice from the upper surface of the bottom. If the ice must be removed very quickly, its removal can be facil-

tated by dipping the bottom of the tray into warm water, or holding it, for a few seconds, over the flame of a gas stove, or in other ways subjecting it to a high degree of heat for a short period, as by this means the bond between the ice and the metal is entirely dissolved, thereby facilitating the release of the ice. Although the heating of the bottom is sometimes desirable, it is not absolutely necessary, as the mechanical force applied by the bending of the bottom is sufficient to release the ice cubes. When the term "cube" is employed, it is intended to cover any ordinary shape of ice, whether it is absolutely cubical or rectangular in shape.

What I claim is:

1. A tray for use in freezing water to form ice cubes of predetermined size and shape comprising, a flexible metal plate forming a bottom, and a mold having a plurality of openings whose walls are formed from rubber, one side of the mold being united with the metal bottom by a water tight joint.

2. A tray for use in freezing water to form ice cubes of predetermined size and shape, comprising a multiple compartment mold whose sides and partition walls are formed from rubber and whose bottom is formed entirely from a piece of resilient bendable sheet metal to one surface of which the rubber sides are vulcanized.
